HEAT PUMP

Emory N. Kemler, Birmingham, Ala., assignor to
Muncie Gear Works, Inc., Muncie, Ind., a corporation of Indiana

Application May 29, 1946, Serial No. 672,924

3 Claims. (Cl. 62—129)

1

This invention relates to heat pumps, wherein a reversible refrigeration cycle is employed for heating the air of a space for winter and cooling it for summer conditions; and structurally it is in the nature of an improvement upon the structure disclosed in my joint application with Marvin M. Smith and Clesant O. Fields, Serial No. 574,478, filed January 25, 1945, issued as Patent No. 2,401,890, June 11, 1946.

The main objects of this invention are to provide an improved construction and arrangement of parts of heat pumps for utilizing the heat of mechanical energy conversion during the heating season, for reducing the effects of waste heat upon the air current during the cooling season, and for accomplishing this end automatically through the operation of other mechanism employed in reversing the function of the refrigeration cycle.

These and other incidental objects are accomplished by the illustrative embodiment of the invention shown in the accompanying drawings, in which:

Figure 1 is a somewhat diagrammatic sectional view, particularly directed to showing the parts in position for directing the air and water as required for the cooling seasons, the section being taken on the line 1—1 of Fig. 2.

Fig. 2 is a section of the same on line 2—2 of Fig. 1.

Fig. 3 is a diagrammatic section similar to Fig. 1, showing, somewhat more in detail, the relation of the air ducts to parts of the refrigeration cycle, as adjusted for the heating season, with some of the mechanism modified to more clearly illustrate certain features.

Fig. 4 is a fragmentary perspective detail of the ventilating shutter for the housing of the motor-compressor unit.

Fig. 5 is a three-dimensional diagram of the shutter mechanism.

In the form shown, the housing 1 is a rectangular insulated shell with an air inlet 2 leading to a lower chamber 3 and an air outlet 4 at its upper part leading to an upper air chamber 4.

The heat exchangers which constitute the condenser 5 and the evaporator 6 are arranged side by side or end to end so as to substantially fill a transverse zone between the chambers 3 and 4.

This heat exchanger zone in the drawings is horizontal and is subdivided into two air ducts by a vertical partition 7 separating the condenser 5 from the evaporator 6. A pair of slideable horizontal partitions or baffles 8 coat with the par-

tion 1 and the housing or other walls to completely enclose and isolate one of the heat exchangers and direct the air flow through the other, and vice versa. These baffles 8 are shiftable across the housing to provide for cooling or heating of the air stream as will hereinafter appear.

The refrigerant circulating system is hermetically sealed and comprises a suction line of piping 9, connecting the receiver 10 through the expansion valve 11 and a thermostatically controlled regulating valve 11.1 to the refrigerant coil 6.1 of the evaporator 6 and with the intake port 12 of the compressor 13, and a pressure line 15 of piping 14, connecting the outlet port 16 of the compressor 13 through the refrigerant coil 5.1 of the condenser 5, to the receiver 10.

The thermostatically controlled regulating valve 11.1 regulates the flow of refrigerant to suit the demand, as may be indicated by a distant thermostat at some suitable place in the space that is to be conditioned.

The refrigerant system is indicated by showing in the drawings only its most essential elements, 25 and omitting many details and refinements of present-day practice which have no direct bearing on the disclosure of the present invention.

In the form shown, the heat pump is arranged to utilize, in the heating season, water as the 30 heat source and the air of the house as the dump for heat of the refrigerant cycle; and in the cooling season, the house air becomes the heat source and water is utilized as the dump for the heat of the refrigerant cycle.

35 The water system comprises a service pipe 16 from a water source, such as a city main or well, a three-way inlet valve 17, branch pipes 18 and 19 leading to condenser water-coil 5.2 and evaporator water-coil 6.2 respectively, and a discharge pipe 20 to which the outlet ends of the water coils 5.2 and 6.2 are connected and which leads to a drain. A thermostatically controlled valve 20.1 controls the flow of water in the water coil 6.2 so as to prevent freezing.

40 The air system comprises suitable ducts to and from the parts of the house to be heated and a blower 21 at the inlet 2 for forcing a circulation of air. The blower 21 and compressor 13 may have a common motor 22 or be separately driven. 45 A water pan 23 collects any water that may drip from the evaporator by reason of condensation of moisture in the air and also serves as a baffle to direct the incoming air over the motor and compressor to cool them and utilize their waste 50 heat during the heating seasons. A humidifier

24 may be located in the compartment 4 for moistening the air in the heating season.

The heat exchanger coils are shown in Fig. 3 as separate water and refrigerant coils for clearness of diagrammatically illustrating the relation and continuity of the air, water and refrigerant circuits, but in practice these coils are more intimately associated.

The positioning of the baffles 8 is controlled, as indicated in Figs. 1 and 5, by a system of belts or cables indicated generally by the numeral 34 with decimal suffixes to indicate individual parts thereof. As shown in Fig. 5, each baffle 8 is operated by a separate endless cable 34. Each cable 34 is attached to its respective baffle 8 by means of stop buttons 36 fixed on the cable and abutting against lugs 35 on the baffles. The cables 34 are driven by a drum, or drums, 37 turned by a crank 38. Each cable may be wound several turns about the drum or drums 37. The flight 34.1 of one cable passes from the drum to pulley 39, then as flight 34.2 which is connected to the upper baffle 8, it passes over pulley 39.1 and then as flight 34.3 it passes over idle pulley 39.2 and back to drum 37. The other cable passes from pulley 37 as flight 34.4 over pulley 40, then as flight 34.5 it is fastened to the lower baffle 8, passes around pulley 41, then as flight 34.6 it is wrapped around a pulley or drum 55, then over idle pulley 40.1 it passes back as flight 34.7 to its driving drum 37.

The three-way valve 17 can be turned to supply water alternatively either to the condenser 5 or to the evaporator 6 and may have its handle 17.1 of lever form and be positioned so that the shifting of baffles 8 from summer to winter position and vice versa will automatically reverse the valve 17. As shown in Fig. 1, the valve lever 17.1 has an eye 17.2 at its end and the cable 34 has stop buttons 36 suitably spaced to accomplish this shifting with appropriate lost motion. In the diagram of Fig. 3, the cable is not shown, but is represented functionally in the form of a traveler rod having the same relation to the lever arm 17.1 of the valve 17 and to the baffle 8 and its parts are numbered to correspond with parts of like function in Fig. 1.

In the present improvement, the arrangement is such that not only is the apparatus so arranged that the motor and the compressor are in the path of the air in its passage to the condenser 5 during the heating season but is also arranged to be separated by movable housing elements so that it is removed from contact with the air that is flowing to the evaporator 6 during the cooling season.

In the form shown, there are movable members illustrated in the form of doors 42 and 42.1, which cooperate with a frame 42.3 to form a housing that isolates the motor and compressor from the other mechanism of the refrigeration cycle, and an adjacent wall of the housing 1 is provided with vents 43 and 44 controlled by a sliding shutter 45 having vents 46 and 47 movable into and out of registry with the wall vents 43 and 44.

The door 42 is controlled by a cable 48; the door 42.1 is controlled by a cable 49; and the shutter 45 is controlled by a cable 50 which extend to drums 51, 52 and 53 respectively on a counter-shaft 54 which is rotated by a pulley 55. As indicated in Fig. 5, the pulley 55 may be driven by one of the flights of the cable 34. As here shown the flight 34.6 is wrapped about the periphery of the pulley 55 before passing to the pulley 40.1.

The drums 51, 52 and 53 are of appropriate

diameters to provide the proper amount of movement to the cables 48, 49 and 50, respectively, corresponding to the amount of travel of the cable 34.6 as the plates 8 travel between their limiting positions for closing off either the condenser or evaporator from the air flowing through the housing. Thus all of the elements that have to be shifted for converting the heat pump from its heating function to its cooling function and controlling the direction of air flow and water flow to correspond are controlled and actuated by the single operating element represented by the crank 38.

The operation of the device shown is as follows:

Except as to parts of the mechanism and equipment having direct bearing on the present invention, it should be understood that many details of a commercial embodiment of the heat pump are omitted from the drawings and this description. For example, it will be understood that apparatus of this kind may be controlled by thermostatic appliances such that the space which is to be conditioned will be maintained at nearly constant conditions, particularly as to temperature regulation by the user. Such apparatus would, of course, include means for starting and stopping the motor, fan and compressor and valve means for cutting off and controlling the flow of water at times when the motor is not operating. Many refinements of details of the refrigerating system which are embodied in commercial applications are also omitted for like reasons.

When the parts are in the position shown in Fig. 3, the fan 21 draws air from the space that is to be conditioned and forces the air to flow through the housing 1 and to be returned from the outlet 4.1 to said space. Since this air current is excluded from the condenser 5, it will pass over the evaporator and be cooled thereby. Any condensation of moisture due to this cooling of the air will be collected and drained away by the drip pan 23. When the parts are in this position, the doors 42 and 42.1 will be closed and will prevent the air flowing through the housing from coming into contact with the motor and compressor. The shutter 45 will be in position to open vents 43 and 44 so that waste heat of the motor compressor will pass to the outside of the housing.

When the motor drives the compressor 14, refrigerant will be drawn from the receiver 10 through the expansion valve 11 where it is expanded so as to cool the evaporator coil 6.1 and will then flow to the compressor 13 where it is compressed, raising its temperature; then the compressed refrigerant vapor passes through the coil 5.1 of the condenser, being condensed by the transfer of its heat to the water coil 5.2 and finally returned to the receiver 10. The water enters from the pipe 16 and is directed by the three-way valve 17 to the pipe 18 and condenser coil 5.2 and after taking up the heat that is dumped into it in the condenser, this water is drained away by the pipe 20.

When the baffle plates 8 are shifted to the right across the partition 7 and into contact with the right-hand wall of the housing 1, as in Fig. 1, the air flow will be directed through the condenser duct and will be excluded from the evaporator. Under these circumstances the device will function as an air heater since the air will then serve as a dump for the heat of the condenser and will carry this heat to the space to be heated.

As the baffle plates 8 are being thus shifted for

air heating, the element 34.5 will slide through the swiveled eye at the end of the lever 17.1 of the valve 17 until it is engaged by the left-hand button 36 and swung to the position for directing the flow of water from pipe 16 to pipe 19 and evaporator coil 6.2 where heat is extracted from this water by the expanding refrigerant in coil 6.1 of the evaporator. After passing through the compressor and evaporator coil, the refrigerant is elevated in temperature, and delivers heat to the air current at the condenser. At such times the doors 42 and 42.1 are open and the shutter 45 is closed so that the air passing through the housing will flow over the motor-compressor and take up heat therefrom in addition to the heat delivered by the condenser to this air.

The refrigerant cycle is the same for both the heating and cooling seasons and in order to change from the function of heating the air to that of cooling the air and vice versa, the operator need only turn the crank 38 in the direction it is free to move and rotate it until its movement is stopped by the engagement of the baffle plates with the opposite wall of the housing. The matter of starting and stopping the mechanism according to the needs of the space to be conditioned is then controlled by thermostatic devices, not shown, the operation of which, however, is well understood.

Although but one specific embodiment of this invention is herein shown and described, it will be understood that numerous details of the structure shown may be altered or omitted without departing from the spirit of the invention as defined by the following claims.

I claim:

1. In a heat pump, a compressor, a condenser and an evaporator connected in refrigeration cycle relation to each other, a housing enclosing said compressor, condenser and evaporator and having an inlet and an outlet for directing air to and from said condenser and evaporator, partition means forming separate air ducts for such air flow, movable closure means for alternatively opening one and closing the other of said ducts, respectively, said compressor being located in said housing between said air inlet and said air ducts, and movable partition means interconnected with said movable closure means and adapted to expose said compressor to the incoming air when flowing to the condenser and to isolate said compressor from such air when flowing to the evaporator, vents for directing external air about said compressor, and closure means for said vents interconnected with said movable partition means to open said vents when said movable partition means are closed and vice versa.

2. In a heat pump, a housing having an air inlet and an air outlet, a refrigerant conduit comprising a condenser and an evaporator in substantial alinement with each other across said housing between said air inlet and air outlet, a

partition separating said condenser and evaporator, a pair of baffle panels coacting with said partition and housing to cut off the air flow at one side of said partition, said baffle panels being shiftable across said partition, adapted in one position to direct the air flow in said housing across said condenser and exclude it from said evaporator and in another position to direct the air flow across said evaporator and exclude it from said condenser, means adapted alternatively to extract heat from said condenser or to supply heat to said evaporator when cut off from the air flow by said baffle means, a compressor for circulating refrigerant in said refrigerant conduit and located in said housing between said air inlet and said baffle panels, and movable partition means operatively interconnected with said baffle panels and adapted to expose said compressor to the incoming air flowing to said condenser and to isolate said compressor from such air flowing to said evaporator.

3. In a heat pump, a housing having an air inlet and an air outlet, a refrigerant conduit comprising a condenser and an evaporator in substantial alinement with each other across said housing between said air inlet and air outlet, a partition separating said condenser and evaporator, a pair of baffle panels coacting with said partition and housing to cut off the air flow at one side of said partition, said baffle panels being shiftable across said partition, adapted in one position to direct the air flow in said housing across said condenser and exclude it from said evaporator and in another position to direct the air flow across said evaporator and exclude it from said condenser, water coils in heat transfer relation to said condenser and evaporator, valve means controlling said water coils, a compressor for circulating refrigerant in said refrigerant conduit and located in said housing between said air inlet and said baffle panels, movable partition means adapted to shift between a setting for exposing said compressor to air flowing from said air inlet to said condenser and a setting for isolating said compressor from air flowing from said air inlet to said evaporator, and a single operating member connected for simultaneously setting said baffle panels, movable partition means and valve means respectively for the heating and cooling functions of the heat pump.

EMORY N. KEMLER.
